UNITED STATES PATENT OFFICE.

RICHARD J. REYNOLDS, OF WINSTON-SALEM, NORTH CAROLINA, ASSIGNOR TO
R. J. REYNOLDS TOBACCO COMPANY, OF WINSTON-SALEM, NORTH CAROLINA,
A CORPORATION OF NEW JERSEY.

TOBACCO-PIPE.

1,292,648.

Specification of Letters Patent. Patented Jan. 28, 1919.

Application filed April 3, 1916. Serial No. 88,493.

To all whom it may concern:

Be it known that I, RICHARD J. REYNOLDS, of Winston-Salem, in the county of Forsyth and State of North Carolina, have invented 5 certain new and useful Improvements in Tobacco-Pipes, of which the following is a specification.

The object of the present invention is to provide a tobacco pipe of such a construction 10 that the nicotin is collected separately from the saliva from the mouth of the smoker and both nicotin and saliva are removed in the act of discharging the ashes from the pipe.

15 The improved pipe construction to obtain this object is illustrated in the accompanying drawings, wherein—

Figure 1, is a sectional view of a pipe containing the improvement. Fig. 2, is a 20 perspective view of a cup which is inserted within the bowl of a pipe. Figs. 3 and 4, are sections of modifications.

Referring first to Figs. 1 and 2, the pipe comprises a bowl A, and a stem B, which 25 may be of any construction and relation to each other and may be of any materials used in pipe making. The bottom of the bowl is in communication with the mouthpiece by means of a passage a, in the stem which 30 leads to the end of the mouthpiece.

Within the bowl is a cup C. This cup is composed of a single piece of sheet metal bent into the illustrated shape. This cup can be made of silver, aluminum, nickel, or other 35 sheet metal.

The cup C, has at its lower end a diaphragm b, which divides the bowl into two chambers. The chamber above the diaphragm b, is open mouthed and receives the 40 tobacco. The chamber D, below the diaphragm is in immediate communication with the stem passage a. This diaphragm b, is conical, or funnel-form, extending upwardly from its periphery to the middle of the bowl.

45 It has an air passage c, at its middle and highest part only. The annular side wall d, of the cup is of a shape to fit the lower portion of the bowl A. It is resilient and sufficiently wide at the mouth so as to be sprung 50 slightly when forced into place in the bowl so as to be adequately held in place by friction. The diaphragm is a proper distance from the mouth of the bowl so as to furnish a sufficiently large chamber E, to receive

a usual charge of tobacco. The cup fits the 55 bowl sufficiently close so that the only passage for air to the stem passage a, is through the single central passage c.

Any nicotin is collected in the channel e, above the diaphragm and below the air passage c, so that it does not pass into the lower air chamber D of the bowl and hence cannot be drawn into the mouth of the smoker. Any saliva from the mouth of the smoker which passes into the chamber D, through the 65 stem passage a, collects therein and does not come in contact with the tobacco while being smoked.

After a charge of tobacco has been smoked the bowl will be turned upside down for the 70 purpose of knocking out the ashes. When the bowl is thus inverted any nicotin which is thus collected in the channel e, will flow outwardly into the ashes and will be discharged with them. Likewise, any saliva which is 75 collected in the chamber D, will run into the funnel constituted by the tapering diaphragm b, and out through the air passage c, into the ash. Accordingly, the nicotin and the saliva will mingle with the ash and 80 will be discharged therewith when the bowl is cleaned.

The pipe provided with the cup C, has the following advantages:

The funnel-form diaphragm of the cup 85 facing upwardly catches the nicotin which accumulates in smoking.

The cup prevents nicotin from intermingling with the saliva from the mouth and thus prevents this disagreeable mixture from 90 getting into the stem of the pipe and then into the mouth of the smoker.

The space or chamber D, under the cup forms a cooling air chamber and acts as a depository for the saliva which comes from 95 the mouth of the user through the pipe stem. A cool smoke is thus secured.

The diaphragm of the cup facing this air chamber D, being funnel-form will, when the pipe is turned over to discharge the 100 ashes, cause the saliva which collects in the chamber to pass through the air hole in the apex of the funnel and mingle with the ashes, being discharged with them. Or, if the ashes have been first removed, the saliva 105 will pass through the hole and be discharged separately.

Disagreeable odors are substantially de-

creased since they are largely due to fine particles of tobacco being drawn into the stem and mixing with the nicotin and saliva. By eliminating this strong odor, sweetness 5 is added to the pipe.

Fig. 4, illustrates a modified construction of the cup. The cup at its rim is provided with a down and out-turning yielding flange *f*, which by its elasticity aids in maintaining 10 the cup in place in the bowl. This yielding down and out-turned flange is compressed when inserted in the pipe and hence acts elastically to hold the cup in place. This figure also illustrates a hooked-end tool *F*, 15 which can be inserted in the air hole *c*, and by means of which the cup can be removed. A similar tool can be used in connection with the cup illustrated in Fig. 1.

Fig. 3, illustrates another modification of 20 the cup *C*. In this case the rim of the cup has an in and down-turned flange *g*, beneath which the hook of the tool *F*, can be inserted for the purpose of withdrawing the cup from the pipe.

25 I claim:

A tobacco pipe having, in combination, a

bowl, a detachable open-mouthed resilient cup shallow relatively to the depth of the bowl and sprung into the bowl and elastically fitting therein at the lower part thereof 30 only, said cup having imperforate side walls and at its lower end a funnel-form diaphragm extending upwardly from the periphery of the cup toward the middle thereof, said diaphragm having an air channel at its 35 apex only, being otherwise imperforate, this funnel-form diaphragm dividing the pipe bowl into two chambers, an upper chamber to receive the charge of tobacco, this chamber having a nicotin collecting annular air channel at its periphery below the air opening at the apex of the diaphragm, and a lower air chamber below the funnel-form diaphragm constituting both a cooling 40 chamber and a chamber for collecting the saliva which may flow from the mouth of the smoker into it through the communicating passage in the stem.

In witness whereof, I have hereunto signed my name:

RICHARD J. REYNOLDS.
